CIGARETTE TRAY

Charles J. Ketcham, Michigan City, Ind.

Application February 2, 1946, Serial No. 645,073

8 Claims. (Cl. 131—240)

1

This invention relates to cigarette trays and holders into which holders the lighted cigarette is placed vertically with its lighted tip downward.

An object is to produce a holder which will instantly stop the smoking of the cigarette when placed and held therein and simultaneously keep the tip alight the longest possible time, and which may be made of material best suited for holder use.

An additional object is the provision of a cigarette tray having one or more hollow supporting projections extending inwardly from the peripheral edge of the tray for supporting a vertical cigarette holder at the inner end, and an ejector mechanism housed in said hollow projection and having a cigarette ejector beneath the holder and an operating member at the opposite end of the projection so that pressure thereon ejects the cigarette from the holder.

Further objects and advantages will appear from the description and claims to follow, in connection with the accompanying drawing which illustrates, by way of example and not of limitation, an embodiment of the invention, and in which—

Fig. 1 is a plan view of one form of tray embodying the invention;

Fig. 2 is a vertical section on the stepped line 2—2 of Fig. 1;

Fig. 3 is a detail section on enlarged scale through the cigarette holder and its mounting; and

Fig. 4 is a detail sectional view on the line 4—4 of Fig. 2.

The tray itself, which may be of any desired form and construction, comprises preferably a zinc casting 10 which may be substantially of the form, size and proportions shown in Figs. 1 and 2 of the drawing, the periphery of which in general comprises the double flanges 11 and 12, the former merging into or from the bottom 13 of the tray and the latter flange having a seat in its lower edge for the reception of the peripheral edge of a bottom plate 14 covering the bottom of the casting. Suitable pins, rivets, screws, or the like, 15 may secure this outside bottom plate to the casting. Small felt pads or a single over-all felt pad, not shown, or similar material may be cemented to the outside of this bottom plate to prevent injury to the surface on which the tray may be placed.

Raised projections 20 are formed preferably at opposite ends of the tray and extend inwardly of the tray from the outer flanges 11 and 17, and since they are duplicates the description of one

will suffice. The side walls at the inner end portion of the projection rise from the bottom 13 and at the outer end portion thereof from the top of the edge flanges 11 and 12. The inner rim flange 11 curves, as at 21, into the side walls of the projections 20 on either side, as indicated, and the outer rim flange 12 forms or merges into the rear vertically fluted wall 22 of the projection. The tops of these projections 20 may be slightly curved transversely, as indicated by the shading. A small extension 23 of the casting walls at the foot of the inner end of the projection forms a vertical guide and seat for the cigarette ejector to be described. All corners are rounded so that the tray may be readily brushed out and cleaned.

Cigarette ejector mechanisms are located largely within these hollow projections or housings 20. Each mechanism comprises a vertical movable ejector 25, normally seated on the top of extension 23 of the projection 20 and directly below the cigarette holder, hereinafter described. The stem or shaft 26 of the ejector is adapted to move vertically and freely in a close-fitting circular portion 26a, Fig. 4, of the casting, the edges of the semi-circular walls of which are spaced vertically, as at 27 and 28 to form slots therebetween, all as further indicated in Fig. 4. The inner end of a flat bar lever 24 is adapted to move up and down in these slots 27 and 28 and carries with it the ejector in such movement. For this purpose the end of the lever is passed through a kerf or slot in the end of stem or shaft 26, and a cross pin 30 therein passes through a short slot in the lever, as indicated.

The lever 24 is pivoted on an inverted bracket 31 suitably secured to a depending cross wall 32 in the inside of the housing 20 and is connected by a similar pin and slot arrangement with the lower end of the shank, shaft or stem 33 of the push-button 34 at the top of the projection or housing 20. This stem 33 has an endwise sliding bearing as at 35 in the casting wall extending from the cross wall 32 to the outer wall 22 of the housing, and between the button 34 and a seat in said wall around the stem 33 is a coil spring 35 having sufficient resilience to raise the button and lower the ejector 25 and sufficiently yieldable to allow the button to be depressed by a slight downward push and the ejector to swing up against the end of the cigarette in the holder and knock it out of the holder so that it falls over into the tray.

The button 34 is preferably substantially square, as indicated in Fig. 1, and conforms transversely

to the curvature of the top of the housing and normally stands with its outer surface substantially flush with the outer top surface of the housing.

The cigarette holder itself, designated herein broadly as H, which may be used with any suitable type of tray or holder support and not limited in its use to the tray disclosed herein, comprises the short or narrow band or ring 40 of thin material into which the lighted end of the cigarette is lightly pressed from above, the holder having the funnel-shaped guiding top 41 and side-supporting strip 42 by which it is secured in a suitable groove to the top inner end of the housing 20, as indicated. This holder H lightly grips the lower end of the cigarette sufficiently to hold it in upright position and with enough pressure to prevent thermal drafts up through and around it. The result is that with the lighted end of the cigarette inserted naturally into the holder with only its burning tip below the lower edge of the holder ring, all smoking stops instantly although the tip continues lighted until the combustion in the tip exhausts itself, which is usually until the oxygen in the air surrounding the lighted tip is consumed. This may continue for several minutes, during which time the cigarette may be removed from the holder and smoked in the usual way without relighting.

The continuation of the lighted condition of the tip is enhanced by making the holder as thin and short as possible under the conditions prevailing, and preferably of low heat conducting metal and supporting the lighted tip free of contact with other parts. But the short thin metal holder tends to expand under the heat from the burning tip and, if the expansion were to become excessive, the cigarette resumes smoking because combustion will continue. To overcome this overexpansion of the holder, there is intimately associated with the holder a material of high heat conductivity and absorption quickly to absorb and carry away the excess heat therefrom which might cause such undesired expansion and to conduct it to a more substantial part of the metallic tray body where it is dissipated. Copper is found to be highly satisfactory for the said material, and accordingly a relatively thick copper strip or bar 43 of the width of the strip 42 is fitted to the holder and intimately connected therewith, as by soldering 44 or the like, and is secured along with the strip in the groove to the top of projection 23 of the tray, as by rivets, screws or the like, as indicated. This effectively prevents such expansion of the holder ring 40 as to prevent the lighted cigarette from smoking after being placed in the holder.

The material of the holder 40 is noncorrosive and such as to prevent clogging up with gummy substance from the burning cigarettes to such an extent that it becomes necessary to scrape or otherwise clean out its inside surface at frequent intervals or to permit its continued use. Smooth-surfaced noncorrosive stainless steel from .015 to .035 inch thick has been found most satisfactory for the purpose, and accordingly the holder 40 is made of it. It is noncorrosive, does not clog, will not stain from burning tobacco, is very smooth and is readily kept clean. In fact, the insertion and withdrawal of the cigarettes accomplishes all the cleaning that may be desired, since nothing present under the conditions tends to cling to its smooth surface. It is of low heat conductivity.

The result is that the cigarette remains smoke-

less continuously while in the holder and the tip of the cigarette remains lighted for several minutes.

It will be understood that holder H including its supporting strip 42 or the equivalent and heat conducting bar 43 may be made as a unit for use on many types of mountings, whether they be ash trays or other ordinary mountings capable of receiving holder H to be used for such a purpose. Also, it will be understood that the heat conducting bar 43 need not be of any particular shape or size as long as it is of sufficient mass readily to conduct the heat from parts 40 and 41 or their equivalent.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. A holder for lighted cigarettes comprising a thin metal ring-like holder adapted to receive the lighted downward end of a cigarette and gently to compress the same just above the lighted tip to stop the cigarette from smoking when first placed in the holder, and excess heat absorbing material connected with the holder to prevent the expansion thereof and the cigarette to smoke while still in the holder.

2. A holder for lighted cigarettes comprising a thin metal ring-like holder adapted to receive the lighted downward end of a cigarette and gently to compress the same just above the lighted tip to stop the cigarette from smoking when placed in the holder, and a relatively thick metal bar intimately connected to said holder to conduct excess heat rapidly away from said holder to prevent expansion of the holder and the cigarette to smoke while still in the holder.

3. A holder for lighted cigarettes comprising a thin stainless steel ring-like holder adapted to be connected to a support and receive the lighted downward end of a cigarette and gently to compress the same just above the lighted tip to stop the cigarette from smoking when placed in the holder, a copper bar joined at one end to the holder and attached to said support quickly to withdraw heat from the holder to prevent expansion thereof and the smoking of the cigarette while in the holder.

4. A holder for lighted cigarettes comprising a thin metallic ring-like holder of low heat conductivity adapted to receive the lighted downward end of a cigarette and gently to compress the same just above the lighted tip to stop the cigarette from smoking when first placed in the holder, and a support for the holder including material of high heat conductivity intimately connected to the holder to prevent expansion of the holder and the cigarette to smoke while remaining in the holder.

5. A holder for lighted cigarettes comprising a metallic ring-like holder adapted to receive the lighted downward end of a cigarette and gently to compress the same just above the lighted tip to stop the cigarette from smoking when first placed in the holder, said ring holder having a supporting strip at one side adapted to be secured to a suitable base, and a copper strip soldered at one end to the holder ring and lying

under and in direct contact with said strip, whereby quickly to withdraw heat from the holder to prevent expansion of the holder and the cigarette to smoke while remaining in the holder.

6. A cigarette tray having one or more raised hollow supporting projections extending substantially inwardly from the rim of the tray, a cigarette holder attached to the inner top portion of the projection and extending over the tray body, ejector mechanism housed within the projection and having a vertically reciprocating ejector spaced well beneath the holder, a push-button seated in the top of the projection adjacent its outer portion, a lever within the projection having one end connected with said ejector and its other end with said push-button, spring means tensioned normally to depress the ejector and raise the button, whereby when pressure is applied to the button the ejector is raised and strikes the cigarette a blow while in the holder and thereby knocks it from the holder and into the tray and upon release of the pressure the ejector and button return to normal position.

7. A cigarette tray comprising a body portion and one or more narrow hollow raised portions extending substantially inwardly from the rim of the body, a cigarette holder secured in a depression in the top of the inner end of one of said raised portions and extending over the tray body, a push-button in a depression in the outer end of one of said raised portions, an ejector beneath the holder, and a mechanism within and enclosed by the raised portion operated by the said button to raise the ejector and expel a ciga-

rette from the holder, and spring means to return the button and ejector to normal position, the button when in normal position and the cigarette holder connection being substantially flush with the top surface of said raised portion.

8. A cigarette tray having one or more raised enclosed housing projections extending substantially inwardly from the rim of the tray, a cigarette holder supported by the upper part of the housing over and above the tray, ejector mechanism within the housing including an ejector spaced substantially beneath the holder and the lower end of a cigarette when in the holder, and a push-button seated in the top of the housing connected to operate said mechanism and thereby by the ejector to cause it to strike and eject the cigarette from the holder.
